WELL DRILLING CONTROL DEVICE

Harold W. Mattingly, Los Angeles, Emmett M. Irwin, Pasadena, George E. Lewis, Alhambra, Richard H. Duval, Pasadena, Ray M. Cheno-weth, West Los Angeles, and Cecil L. White-head, Pasadena, Calif., assignors to Cooperative Development Co., Los Angeles, Calif., a corporation of California

Application February 6, 1939, Serial No. 254,794

15 Claims. (Cl. 255—1)

Our invention relates to well drilling control devices and has particular reference to an instrument which may be attached to the drill string adjacent the bit during drilling operations for transmitting to the ground surface information as to the angle and direction of inclination of the well bore and orientation of the drilling tools.

In the drilling of oil wells it is the common practice to either locate the derrick directly above the oil pool which is to be tapped and to attempt to drill the well in a true vertical direction, or to locate the derrick at some location offset horizontally from the pool and to cause the well bore to deviate from the true vertical in the proper direction toward the pool.

Drilling technique has developed sufficiently that a driller can cause the bit to be deflected substantially as desired. Thus, if the driller knows or can readily determine whether the bit has deviated from the prescribed course, he may return the bore to the prescribed course before any appreciable amount of hole has been drilled in the wrong direction. Thus, he may avoid a great waste of time and expense which is now occasioned by drilling an appreciable amount of the bore and then interrupting the drilling and surveying the bore only to discover that a considerable amount of footage has proceeded in the wrong direction.

It is, therefore, an object of our invention to provide a drilling control device which includes a self-contained instrument permanently secured to the drill string near the boring bit and which may be placed into active operation immediately upon cessation of rotation of the drill string for measuring any angle of inclination of the well bore from the vertical and measuring the compass direction of any such inclination and for transmitting this information immediately to the ground surface.

Another object of our invention is to provide a drilling control device of the character set forth wherein the measurements or determinations are transmitted to the ground surface without employing interconnecting transmission mediums other than the materials and equipment employed for ordinary drilling operations.

Another object of our invention is to provide a drilling control device of the character set forth in the preceding paragraphs which will also measure and transmit to the ground surface the compass direction of some predetermined reference point on the drilling tools to permit such

instrument to be employed in the orientation of drilling tools within the well bore.

Another object of our invention is to provide a control device of the character set forth wherein the information may be received at the ground surface and there recorded to provide a visual record of the measurements made by the instrument.

Other objects and advantages of our invention 10 will be apparent from a study of the following specification, read in connection with the accompanying drawings, wherein:

Fig. 1 is a diagrammatic representation of an oil well bore during the drilling thereof with the 15 boring equipment situated at the bottom of the bore, together with the instrument of our invention;

Fig. 2 is an enlarged elevational view partly in 20 section illustrating the relationship between the boring bit, the sub positioned directly thereabove and the manner in which our instrument may be secured to the sub;

Fig. 3 is a horizontal section taken substantially 25 along the line III—III of Fig. 2 to illustrate further details of the manner of securing our instrument to the sub;

Fig. 4 is a longitudinal section of a portion of 30 an instrument proper embodying our invention with parts broken away to show the relative relationships between the various elements employed;

Fig. 4A is a longitudinal section of another portion of the instrument proper consisting of a continuation of the instrument shown in Fig. 4;

Fig. 5 is an enlarged longitudinal section of a 35 portion of the equipment illustrated in Fig. 4 and showing the details of construction of a commutating device, a sequence interlocking device, an instrument orientation analyzing device, and a compass device, together with the necessary driving and interconnecting equipment;

Fig. 6 is a diagrammatic representation in perspective section illustrating a portion of the equipment illustrated in Fig. 5;

Fig. 7 is a longitudinal sectional view similar 45 to Fig. 5 but showing the details of construction of the equipment located at the extreme upper end of the instrument and comprising a means for transmitting the instrument determinations to the ground surface;

Fig. 8 is a schematic representation of the 50 equipment and electric circuits employed in the receiving device disposed at the ground surface;

Fig. 9 is a longitudinal section through the receiving element which is attached to the goose neck at the top of the "kelly" to receive the trans-

missions from the instrument disposed in the bore hole;

Fig. 10 is a horizontal section taken substantially on the line X-X of Fig. 5 to illustrate additional details of construction of the compass device employed;

Fig. 11 is a longitudinal section taken substantially along the line XI-XI of Fig. 12 and illustrating still another portion of our instrument and the details of construction of a normally open type of agitation or vibration responsive switch;

Fig. 12 is a horizontal section taken substantially along the line XII-XII of Fig. 11 showing additional details of construction of this type of agitation switch;

Fig. 13 is a view similar to Fig. 11 but illustrating the details of construction of a normally closed type of agitation switch;

Fig. 14 is a schematic wiring diagram illustrating the electrical connections employed between the various instrumentalities carried by the instrument proper; and

Fig. 15 is a diagrammatic representation of the type of chart and recording which will be made thereon when the instrument is employed to survey a well following a certain assumed course.

Referring to the drawings, we have illustrated in Fig. 1 a typical well drilling installation wherein a well bore 1 is drilled by a drill bit 2 carried by a sub 3 connected to the lower end of a drill string 4 comprising a plurality of sections of drill pipe extending to the ground surface 5 and coupled to a rotary table 6 driven by means of power apparatus 7. The drill string 4 is supported from a swivel 8 which is suspended from a travelling block 9 of a block and tackle assembly including a crown block 10 supported at the top of a derrick 11.

The swivel 8 normally constitutes a connection between the drill string 4 and a mud hose 12 connected to any suitable pumping apparatus whereby drilling fluid or mud may be circulated through the drill string 4 to carry the cuttings away from the bit 2.

The well bore 1 is illustrated in Fig. 1 as being disposed in a true vertical direction throughout the upper portion of its length while the lower end of the well bore 1 is illustrated as being deviated from the vertical at the point 13. The change in direction occurring at the point 13 may be either accidental or intentional for the purpose of directing the well bore toward an oil pool disposed in an off-set location relative to the starting of the bore 1. In either event, it is necessary, in order to direct the drilling of the well bore 1 in the proper direction, that the person controlling the drilling operation be apprised of the angle of inclination from the vertical of the lower portion of the well bore and the compass direction of such deviation.

We accordingly provide a survey instrument 14 which may be permanently secured to the sub 3 and be continuously disposed near the bit 2. The instrument 14 is preferably housed in a cylindrical casing 15 inserted in a recess 16 provided in the wall of the sub 3 and spaced also from the mud fluid passage therethrough so that the central opening through the drill string is unimpaired and there are no protuberances which extend beyond the normal periphery of the sub 3. A removable cover member 17 attached by bolts 18 may secure the instrument 14 within the recess 16. The recess 16 is so positioned that the longitudinal axis of the housing is always main-

tained parallel to the longitudinal axis of the bit, sub, or drill string so that the axis of the instrument housing 15 will be disposed in the same direction as the direction taken by the well bore.

While various types of orienting devices may be employed in the instrument of our invention, the preferred embodiment thereof includes a magnetic compass needle and the sub 3 is, therefore, preferably constructed of manganese steel or other suitable non-magnetic material or alloy. The instrument 14 is composed of a plurality of cooperating mechanisms carried by the housing 15 which, as illustrated in Figs. 4 and 4A, may comprise an elongated tubular shell fitted at its upper and lower ends with suitable closures or caps 19 and 20. Space for electrical connections between the various devices contained within the housing may be provided by employing an inner cylindrical shell 21 which is spaced from the inner surface of the casing 15 by spacers 22 to define an annular space 23 therebetween.

Within the interior of the inner shell 21 we have secured a plurality of angle measuring devices 24 constructed as described in detail in a copending application Serial No. 162,792, filed September 7, 1937, by Emmett M. Irwin et al. and each includes a conically depressed surface 25 upon which is placed a ball 26 adapted, upon inclination of the instrument to a predetermined angle, to roll to the outside edge of the surface 25 and electrically interconnect the surface 25 with a contact ring 27 mounted on an insulated support 28 for the supporting surface 25, whereby the number of such devices which have the rings 27 and surfaces 25 thereof electrically interconnected indicates the extent of any angular deviation of the housing 15 from the vertical.

Below the angular measuring devices 24 we secure a commutating and sequencing device 29 which may include a commutator ring 70 supported within the casing 21 by an insulated supporting plate 71 extended transversely thereacross and insulated therefrom by an insulating liner 72. The commutator ring 70 includes three main sections, two of which, indicated at 73 and 74, comprise arc-shaped portions of electrically conductive material each embracing substantially 120 degrees and separated from each other by means of an insulating spacer 75. The remaining one-third of the ring 70 is composed of a plurality of commutator segments 76 separated from each other by insulating material 77.

A wiper arm 78 is arranged to be selectively positioned in contact with any of the segments 73, 74 or 76 and may include an arm portion 79 engaging the upper surface of the commutator ring 70 and carrying a hub portion 80 secured to and insulated by insulating material 82 from a drive shaft 81 journaled for rotation at its upper end by a bearing 83. The drive shaft 81 may be driven by an electric motor 30 whose shaft 84 is coupled to the drive shaft 81 through suitable reduction gearing 31.

The sequencing device 29 also includes another commutator ring 85 which is similar in construction to the commutator ring 70 previously described but differs therefrom in that it comprises a substantially full circle segment 81 of electrically conductive material interrupted at a single point by an insulating portion 88. The associated arm 86 is drivably secured to the drive shaft 81 and is electrically connected thereto.

A bore hole orientation analyzing device 33 is disposed below the motor 30 and includes a commutator ring 89 which may comprise a plurality

of electrically conductive commutator segments 90 separated from each other by very thin insulating spacers 91. The commutator ring 89 is mounted on an insulating supporting member 92 carried by an insulating liner 93 secured within the inner sleeve 21. An electrically conductive bearing plate or raceway 94 rests upon the supporting plate 92 and supports an electrically conductive ball 95. The upper surface of the raceway plate 94 is upwardly convex so that the ball 95 may be continuously urged by gravity outwardly into engagement with the commutator ring 89. The raceway 94 may be insulated from the segments 90 by an insulating ring 96 interposed between the periphery of the raceway 94 and the inner surface of the commutator ring 89. The insulating ring 96 is preferably undercut to provide an annular trackway in which the ball 95 may roll and electrically interconnect the plate 94 and one of the segments 90.

The commutator assembly is mounted perpendicularly to the longitudinal axis of the instrument so that upon inclination of the instrument from the vertical the ball 95 will roll to the low side of its trackway to define a housing low point disposed diametrically opposite to the actual direction of deviation of the well bore. The angular location of the ball member 95 relative to a reference point on the instrument may be measured by a wiper arm 97 which has a contacting arm portion 98 engaging the upper surfaces of the commutator segments 90 and adapted to be so rotated as to bring the contacting end 98 thereof into contact with each of the segments 90 in sequential order by means of a drive shaft 99 to which an insulated hub portion 100 of the arm is secured. The drive shaft is connected to the electric motor 30 through reduction gearing 35 and a suitable speed governing mechanism 32.

A compass point analyzing device 34 is mounted below the orientation device 33 and comprises separate coacting units including an analyzing device having a commutator ring 101 (substantially identical in construction to the commutator 89 previously described with the exception that no ball member or provision therefor is made) adapted to cooperate with a wiper arm 102 secured to the drive shaft 99, and a compass unit which includes a magnetic compass needle 103 and control mechanism therefor indicated generally at 104. The compass needle 103 (see Figs. 5 and 6) comprises a permanently magnetized needle bar provided with a contacting element 105 adapted to be moved into engagement with the lower surfaces of the segments of the commutator ring 101. The compass needle 103 may be supported by a pivot member 107 extending upwardly from a supporting plate 107a and terminating at its upper end in a pivot point 108. The needle 103 may be attached to a pivot plate 109 which carries a downwardly extending boss member 110 defining an upwardly extending tapered recess 111 adapted to encompass the pivot member 107 and to provide a coacting pivot seat for receiving the pivot point 108. The dimensions of the needle 103, the supporting plate 109 and the boss 110 are preferably chosen such that the center of gravity of the system is disposed below the pivot point 108, whereby the compass needle assembly will be stably supported for practically frictionless rotation upon the pivot 108.

The pivot mechanism may be protected from the vibrations and shocks encountered during the drilling operations by lifting the compass needle

assembly out of contact with the pivot point and clamping it in a locked position against the lower surface of the commutator ring 10, by a compression spring 114 enclosed in a suitable housing 115 and bearing against an abutment 116 on the lower end of a solenoid armature 112 adapted to freely slide within a solenoid coil 113. The armature 112 carries at its upper end a non-magnetic extension portion 117 which is provided with a plurality of upwardly extending spider arms 118 passed through suitable openings 119 in the plate 107a and having feet portions adapted to engage the under-surface of the plate 109. The spring 114 thus normally lifts the pivot seat 111 out of engagement with the pivot point 108 and clamps the compass needle 103 into engagement with the lower surface of the ring 101 to press the contact member 105 into engagement with one of the commutator segments. An insulating spacer 106 may be provided at the opposite end of the needle to prevent any other part of the needle from engaging the segments of the commutator 101. Energization of the solenoid 113 lowers the needle 103 upon its pivot 108.

The manner in which the previously described equipment is coordinated and how this equipment functions to provide at the ground surface the necessary data for permitting a drilling operator to determine the exact course being taken by the well bore may best be understood by having reference to the schematic wiring diagram (Fig. 14) and by carrying forward the description of the electrical connections simultaneously with the description of the operation of the instrument.

The instrument includes a self-contained power supply such as batteries 39 mounted in the lower part of the inner casing 21 and the negative side of such batteries are grounded to the instrument case by means of a series circuit including a conductor 137, normally open contacts of an agitator switch 36, a conductor 138, and normally closed contacts of an agitation switch 38. The agitation switch 36 is arranged to close its contacts a predetermined time after the stopping of the drilling operation to thereby complete the above described circuit and place the instrument in an operative condition.

The agitation or vibration responsive switch 36 may be constructed in the manner described in detail in a copending application Serial No. 233,208, filed October 4, 1938, by Emmett M. Irwin et al., such construction being illustrated in Figs. 11 and 12. Briefly, the switch mechanism 36 comprises a cylindrical housing unit 121 of insulating material adapted to receive and closely encompass an electrically conductive ball 122. A housing bottom 123 carries a pair of electrical contact members 124 in a position to be interconnected by the ball 122 when in its lowermost position. A passage 125 communicating between the bottom and the top of the space within the housing 121 is formed in a body member 126 which carries the housing member 121. A check valve 127 in the passage prevents the fluid with which the housing 121 is filled from flowing from below the ball exteriorly through the passage 125 to the space above the ball 122. The ball 122 is fitted closely within the housing 121 to act as a piston and tend to force the fluid which is below the ball through the passage 125. Such fluid flow is prevented by the check valve 127 and the fluid holds the ball in an elevated position relative to the contact members 124.

An adjustable bleeder valve 128 forming a by-

pass around the check valve 127 through which the fluid may slowly flow permits the ball 122 to descend toward the contacts 124. The vertical component of vibration to which this device is subjected during drilling operation will, by reason of the inertia of the ball 122 and the one-way action of the check valve 127, cause the ball 122 to rise in the housing 121. As soon as vibration ceases, as upon the stopping of the drilling operations, the ball 122 will slowly settle by gravity toward the contacts 124 and establish an electrical circuit therebetween a predetermined adjustable time after the cessation of the drilling operations.

The agitation switch 38 is responsive to protracted idle periods to place the instrument in an inoperative condition and a similarly constructed agitation switch 37 is employed for controlling the solenoid 113 of the compass clamping mechanism as described hereinafter. The switches 37 and 38 are similar in principle to the switch 36 previously described but are provided with normally closed contacts and may be constructed as illustrated in Fig. 13. A cylindrical passage 129 is formed in a body member 130 and a ball member 131 is closely fitted therein. The passage 129 is filled with oil and an auxiliary control passage 132 communicates between the upper and lower ends of the cylindrical passage 129 and has placed therein a check valve 133 and a by-pass control valve 134 arranged to by-pass fluid from within the housing 121 into the passage 132 around the check valve 133.

The electrical circuit may be established by the ball 131 between the electrically conductive walls of the passage 129 and a flexible conical compression spring 135 which is disposed immediately above the ball 131 and secured to the body member 130 from which it may be insulated by an insulating bushing 136. Vibrations due to drilling operations will cause the ball 131 to rise in its cylinder 129 and upon cessation of drilling operations the ball 131 will slowly settle.

We prefer to make the compression spring 135 with such resilience that upward movement of the ball 131 will be permitted and the electrical circuit between the body member 130 and the spring 135 will be completed by the ball member. When the ball 131 settles to a position corresponding to the unflexed position of the spring 135, the circuit will be broken by the separation of the ball therefrom.

The adjustment of the agitation switch 38 is so arranged that the contacts thereof will remain closed a sufficient length of time to allow the instrument to operate to make one or more complete sets of survey readings, after which these contacts open to place the instrument in an inoperative condition.

A conductor 139 extends from the battery positive to one of the terminals of the motor 30 and the other terminal is connected by a conductor 140 to ground so that the motor will be energized by the closing of the agitation switch 36 to start the sequential operation of the equipment.

We employ a mechanically operated inter-lock or timing means which operates each time the instrument is placed in operation to maintain the instrument operating during a complete time cycle of operations as represented by a complete revolution of the wiper arm 86 which is connected to ground, the commutator ring 87 being connected to the negative battery terminal through a conductor 141.

The wiper arm 86 rotates in the direction indi-

cated by the arrow 142 and establishes a holding circuit across the agitation switches 36 and 38 so that the equipment will be maintained in operation after opening of either of the switches 36 or 38 until the wiper arm 86 is rotated into contact with the insulating segment 88 at which time the circuit 141 will be interrupted.

The circuits for transmitting to the ground surface the angle of inclination of the well bore from the vertical include a series circuit extending from the positive battery terminal through a conductor 143 to one terminal of a solenoid 46 forming a part of a transmitting device 40 adapted to transmit sound signals to the ground surface upon energization of the solenoid 46, and from the other terminal of the solenoid 46 through a conductor 144 to the wiper arm of the commutating device 70 through a spring brush 145 engaging the hub portion 80 of the wiper arm 78. The first of the segments 76 is connected directly to ground by means of a conductor 146 and each of the remaining segments 76 are connected by conductors 147a, 147b and 147c through 147h to the contact ring portions 27 of each of the angle measuring devices 24, the supporting plane portions 25 of each of these devices being grounded to the instrument case.

The transmitter 40 may be constructed as described in the aforementioned copending application, Serial No. 233,208, such construction being illustrated in Fig. 7 as including a diaphragm 41 secured between the upper cap 19 and a clamping ring 42 secured to the casing 15. The diaphragm 41 is equipped with an acoustic impedance-matching coupling device comprising an elongated rod 43 secured to the diaphragm 41 and carrying at its lower end a rod weight 44. The rod weight 44 is disposed in a position to be engaged by the upper end of a solenoid armature 45 upon upward movement thereof in response to energization of the solenoid coil 46.

Proper proportioning of the dimensions of the rod 43 and the rod weight 44 relative to the dimensions and material employed in the diaphragm 41 causes this assembly to operate to transmit to a fluid in contact with the diaphragm 41 sound vibrations of a predetermined frequency when the rod weight 44 is struck a sharp blow. A spring 47 surrounds a tail-piece 48 secured to the lower end of the armature 45 for balancing the weight of the armature and an adjusting means 49 permits the normal positioning of the armature 45 to be adjusted as desired.

An opening 50 communicates with the fluid passage in the sub 3 (identified in Fig. 2 by the reference character 51) and extends to a position permitting the drilling fluid to contact the diaphragm 41. A small bleeder hole may communicate between the passage 50 and the exterior of the sub 3 so that air which might otherwise be trapped in the dead-end passage 50 may be discharged outwardly.

We have illustrated diagrammatically in Fig. 8 equipment which may be employed at the ground surface for receiving the signals produced by the transmitting device 40 as including a sound or pressure wave responsive mechanism 53 which is exposed to the effect of the pressure waves sent up through the liquid column. The mechanism 53 may be enclosed in a housing 54 attached to or formed as an integral part of a gooseneck 55 disposed above the swivel 8 and connected to the mud hose 12. The sound responsive device 53 may be constructed as illustrated and described in the aforementioned copending application,

Serial No. 233,208, such construction being illustrated in Fig. 9 as including a collar 60 securing the housing 54 to a boss 61 provided on the gooseneck 55. The collar 60 secures a diaphragm 62 in sealing position across an opening in the boss 61 so as to lie in direct contact with the mud fluid which is circulated through the gooseneck 65. The diaphragm 62 is provided with an impedance-matching coupling device including a rod 63 secured to the diaphragm 62 and carrying at its upper end a rod weight 64. The rod weight 64 and the rod 63 may be held in a centralized position within the housing 54 by means of a flexible spider 65. A suitable microphone or other translation mechanism 66 is either secured to the rod weight 64 or held in a position cooperating therewith so that vibrations of the rod weight 64 resulting from the impact of sound waves on the diaphragm 62 will cause a similar change in electrical conditions existing in a pair of microphone leads 67.

We employ, in the preferred embodiment of our invention, a "crystal" microphone which is peculiarly adapted to be secured to and form a part of the rod weight 64. By properly selecting the weights and dimensions of the rod weight 64, the microphone 66, the sound rod 63, and the diaphragm 62 the system may be tuned to the same frequency as that transmitted by the transmitting device 40 so that extraneous noises will be largely excluded.

A suitable microphone transformer 68 may be employed to match the impedances of the microphone 66 and a transmission line 69 extended to an amplifier 56. The amplifier 56 may operate a recorder 57 or an individual translation device such as earphones 58 and the circuit may include a band-pass filter 59 to further limit the response of the recorder 57 and earphones 58 to the signals emitted by the transmitter 40.

The manner in which the previously described angle measuring devices cooperate to actuate the transmitting device 40 and transmit to the ground surface the determinations of the angle of inclination of the well bore from the vertical through the agency of the sequencing device may best be understood by assuming certain operating conditions and describing the operations of this equipment under such assumed conditions.

Assume, for example, that the well bore is deviating one and one-half degrees from the vertical and that the angular interval of each of the angle measuring devices 24 is one-half of one degree so that three of the balls 26 will have electrically connected their associated contact rings 27 to ground. As soon as the wiper arm 78 is moved across the commutator segments 75, the circuit from the battery positive terminal through conductors 143, the solenoid 46, and conductor 144 will be completed four times, once upon contacting the first segment 76 and once for each of the three succeeding segments which are grounded through circuits 147a, 147b and 147c, to energize the solenoid 46 a corresponding number of times and cause four sound impulses to be transmitted to the ground surface and recorded on the recorder 57.

We have illustrated in Fig. 15 the appearance of a section of tape 148 produced by the recorder 57 upon which are illustrated recordings made by the recording device 51 under these assumed operating conditions. The first signal produced by the transmitter 40 will produce one mark 149 on the tape and the three succeeding impulses

transmitted to the ground surface will be recorded on the tape 148 as marks 150, 151 and 152. The first mark 149 indicates to the operator the starting point of a time cycle of operation, and the remaining three marks 150, 151 and 152 indicate that three of the angle measuring devices 24 are in the displaced position and that the angle of deviation of the well bore from the vertical is equal to three one-half degree increments or one and one-half degrees.

As soon as the wiper arm 78 has traversed all of the contact segments 76 to complete a first of three time periods, it comes into contact next with the transfer segment 73 which is connected by conductor 153 to the wiper arm 97 of the orientation devices 89 through a brush mechanism 154.

The wiper arm 97 may be caused to traverse all of the segments 90 during the second time period while the wiper arm 78 is in contact solely with the segment 73 by so arranging the ratios of the reduction gearings 31 and 35 that the wiper arms 97 and 102 will make three complete revolutions during the time the wiper arms 78 and 86 are making one complete revolution.

The first of the segments 90 which will be contacted by the wiper arm 97 at the start of the second time period is grounded by conductor 155 to provide a reference point on the instrument housing so that engagement of the arm 97 with this grounded segment will complete a circuit through the transmitting solenoid 46 and conductors 143, 144, 153 and 155 to cause operation of the transmitting device and produce a mark 156 on the chart 148 comprising a chart reference point indicating the time at which the wiper arms were moved to coincidence with the housing reference point.

Since the instrument is inclined, the ball member 95 rests on the low side of its raceway and establishes an electrical circuit between one of the commutator segments 90 and the grounded supporting surface 94. Assume, for example, that the bore hole is inclined in a direction due east and that the instrument housing reference point is disposed in a position 135 degrees west of north. In the assumed case the wiper arm 97 will come in contact with that one of the segments 90 which has been connected to ground by means of the ball 95 after 225 degrees of rotation, at which time the signalling circuit will be completed through the transmitting solenoid 46 so as to cause another mark 157 to be made on the chart 148.

Upon arrival of the wiper arm 97 at its original starting point the wiper arm 78 will cross the insulating segment 75 and establish contact between the conductor 144 and the next transfer segment 74 which is connected by conductor 158 to the wiper arm 102 through a suitable brush mechanism 159.

The solenoid 113 is connected in a circuit 160 which extends from the battery positive terminal and includes contacts of the normally closed agitation switch 37. The solenoid 113 is thus energized simultaneously with the motor 30 to lower the compass needle 103 on to its pivot point 108. The needle then aligns itself with the direction of the earth's magnetic field so that the contacting element 105 carried thereby is pointing north. After sufficient time has elapsed to permit the compass needle 103 to properly orient itself, circuit 160 is opened by the agitation switch 37, thereby de-energizing the solenoid 113 and

permitting the spring 114 to clamp the compass needle 103 in its upper position and ground the commutator segment of the compass point analyzing device which is disposed in the same angular position as is the compass needle 103. This operation is completed before the start of the third and last time period.

At the beginning of the third time period the compass needle 103 will thus be located in a position disposed 135 degrees east of the starting point of the wiper arm 102 and will occupy its clamped position grounding that one of the commutator segments which is disposed in this location. The first commutator segment is grounded by conductor 161 so that the beginning of the third time period will be indicated by an impulse transmitted to the ground surface and producing a third monitor recording 162 on the chart 148. Continued rotation of the wiper arm 102 will bring it into contact with the grounded commutator segment and transmit to the ground surface and cause to be recorded on the tape 148 a compass point indication 163. Thereafter the wiper arm 102 will be moved to the end of its full circle of rotation at which time wiper arms 78 and 86 of the commutating and sequencing devices will arrive at their original starting positions to indicate the completion of the first time cycle.

If, at this time, the agitation switch 38 has opened its contact, the interruption of the holding circuit 141 at segment 88 will stop the equipment. If, however, at this time the agitation switch 38 has not interrupted the circuit 137—138, the device will operate to repeat exactly the cycles of operation previously described until such time as switch 38 interrupts the circuit 137—138. The instrument will stop after it completes the particular time cycle in which it was operating at the time this agitation switch operated. After the instrument has operated in the above described fashion, the drilling operator may again start the drilling operation to continue the extension of the bore hole along the course indicated by the instrument. Resumption of the drilling operations will place the agitation switches 36, 37 and 38 in their non-operated position so that whenever the drilling operator desires to make another survey to check the course being taken by the well bore he may do so by again stopping the rotation of the drill string.

Reference to Fig. 15 will indicate that each of the three monitor marks 149, 156 and 162 are spaced from each other on the chart 148 a distance 164 representing either 360 degrees of rotation of the wiper arms 97 and 102 or the length of each of the three time periods. The governor 32 insures constancy of speed of rotation of various wiper arms and the tape 148 is likewise advanced at a constant speed so that the distances separating these monitor indications will be substantially constant.

By comparing the distance 164 with a distance 165 (measured between the second monitor indication 156 and the bore hole position indication 157) and with a distance 166 (measured from the monitor mark 162 to the compass point indication marked 163), the direction of the deviation of the well bore may be determined. Under the assumed conditions the angular distance of the housing reference point to the point which caused transmission of the mark 157 is 225 degrees so that the linear distance 165 will bear the same ratio to the linear distance 164 as does 225 degrees to 360 degrees. In the same fashion, comparing the linear distance 166 to the linear distance

164 will reveal that the dimension 166 represents an angle of 135 degrees. The difference between these angular measurements; namely, 90 degrees, represents the angular disposition of the direction of the bore hole relative to the magnetic north direction.

The various wiper arms are preferably rotated in a clockwise direction and since the dimension 166 is smaller than the dimension 165, the deviation of the well bore is east of north 90 degrees or due east.

The dimension 166 when compared to the dimension 164 indicates the angular position of the instrument housing reference point relative to the predetermined compass direction indicated by the compass needle 103. Since the relative angular positions between the instrument reference point and the direction along which a whipstocking tool will operate may be easily determined prior to the insertion of the tool into the well, the dimension 166 provides the drilling operator with a basis from which he may readily determine the actual compass direction along which the whipstocking tool will drill. Thus, the instrument may be employed at any time for the purpose of initially placing a whipstocking tool in the correct position to deviate the well bore from its present course along a new prescribed course or for the purpose of checking at any time the course along which such a whipstocking tool is then operating.

We have thus provided an instrument which may be permanently associated with the boring bit so that the direction or course of the well bore may be very quickly and readily determined without requiring the insertion of an instrument into the well bore or the removal of tools from the well in order to obtain the necessary survey information.

While our instrument is particularly adapted to substantially permanent association with the drill string, the instrument and housing 15 comprise a self-contained unit which may be lowered into the well bore or into the mud fluid passage in the drill string by means of a sand line in order to survey a completed or partially completed well.

While we have shown and described the preferred embodiment of our invention, we do not desire to be limited to any of the details of construction shown or described herein, except as defined in the appended claims.

We claim:

1. In a device for determining the angular position of a well tool insertable in a well bore and having a tool reference point thereon, the combination of: a housing having a housing reference point thereon; means mounting said housing upon said well tool with said housing reference point in a predetermined angular position relative to said tool reference point; a device in said housing for at any time measuring the angular relation between a predetermined compass direction and the location of said housing reference point; timing means in said housing for defining a time cycle; signal producing means in said housing; and means coacting with said timing means for actuating said signaling means to produce a pair of signals, the relative position of which in said time cycle are representative of the angular disposition of said housing reference point relative to said predetermined compass direction.
2. In a device for measuring the inclination and direction of a well bore, the combination of:

a housing; means mounting said housing upon a drilling tool insertable in said bore; a device in said housing for measuring the angle of inclination of said tool from the vertical; mechanism in said housing for measuring the angular position of the low point of said housing relative to a predetermined reference point on said housing; compass means in said housing for measuring the compass direction of said reference point; and means for transmitting to the ground surface the measurements made by said device, mechanism, and compass means.

3. In a device for measuring the direction of deviation of a well bore from the vertical, the combination of: a housing; means mounting said housing upon a drilling tool insertable in said bore; a device in said housing for determining the low point of said housing relative to a predetermined reference point on said housing; mechanism in said housing for measuring the compass direction of said reference point; timing means on said well tool for defining a time cycle; signal producing means in said housing; and means for successively connecting said device and said mechanism to said signaling means in a predetermined sequential order to produce signals, the position of which in said time cycle is representative of the measurements made by said device and said mechanism.

4: In a device for measuring the inclination and direction of a well bore, the combination of: a housing; means mounting said housing upon a drilling tool insertable in said bore; a device in said housing for measuring the angle of inclination of said drilling tool from the vertical; orientation means in said housing for determining the low point of said housing relative to a predetermined reference point on said housing; mechanism in said housing for measuring the compass direction of said reference point; timing means in said housing for defining a time cycle; signal producing means in said housing; and means coacting with said timing means for successively connecting said device; orientation means, and said mechanism to said signaling means in a predetermined sequential order to produce signals, the position of each of which in said time cycle is representative of the measurements made by said device, orientation means and said mechanism.

5. In an oil well drilling control device, the combination of: an instrument comprising a housing detachably secured to a drilling tool insertable in said bore, a device in said housing for measuring the angle of inclination of said drilling tool from the vertical, a mechanism in said housing for measuring the compass direction of the inclination of said drilling tool from the vertical, timing means in said housing for defining a time cycle, signal producing means in said housing, and means coacting with said timing means for successively connecting said device and said mechanism to said signaling means in a predetermined sequential order to transmit to the ground surface a plurality of signals, the position of each of which in said time cycle is representative of the measurements made by said device and said mechanism; and translation means at the ground surface comprising a receiving device for receiving said signals, and a recording device actuated by said receiving means for recording the positions of said signals in said time cycle to provide a visual record of the angle of inclination of said well bore from the vertical and the compass direction of said inclination.

6. In an oil well drilling control device, the combination of: an instrument comprising a housing detachably secured to a drilling tool insertable in a well bore, a device in said housing for measuring the angle of inclination of said drilling tool from the vertical, orientation means in said housing for determining the low point of said housing relative to a predetermined reference point on said housing, mechanism in said housing for measuring the compass direction of said reference point, timing means in said housing for defining a time cycle, signal producing means in said housing, and means coacting with said timing means for successively connecting said device and said orientation means and said mechanism to said signaling means in a predetermined sequential order to produce a plurality of sets of signals whose position in said time cycle is representative of the measurements made by said device and said orientation means and said mechanism; and translation means at the ground surface comprising a receiving means for receiving the signals transmitted by said instrument, and a recording means actuated by said receiving means for recording the position of said signals in said time cycle to provide a visual record of the angle of inclination of said well bore from the vertical, the compass direction of said instrument reference point, and the angular position of said reference point relative to the direction of deviation of said well bore.

7. In a device for measuring the direction of a well bore, the combination of: an instrument housing insertable in said bore; means in said housing defining a reference point thereon; a device in said housing for defining a housing low point when said housing is disposed at an angle to the vertical; compass means in said housing for defining a predetermined compass direction; signal producing means in said housing; timing means in said housing for defining a time cycle including a pair of time periods; transfer mechanism coacting with said timing mechanism for associating one of said time periods with said device and for associating another of said time periods with said compass means; means cooperating with said device and said signaling means for actuating said signaling means to produce a pair of signals whose relative positions in said first time period are representative of the angular position of said low point relative to said reference point; and means cooperating with said compass means and said signaling means for actuating said signaling means to produce another pair of signals whose relative positions in said other time period are representative of the angular position of said reference point relative to said predetermined compass direction.

8. In a device for measuring the direction of a well bore, the combination of: an instrument housing insertable in said bore; means in said housing defining a reference point thereon; a device in said housing for defining a housing low point when said housing is disposed at an angle to the vertical; compass means in said housing for defining a predetermined compass direction; signal producing means in said housing; timing means in said housing for defining a time cycle including a pair of time periods; transfer mechanism coacting with said timing mechanism for associating one of said time periods with said device and for associating another of said time periods with said compass means; means cooperating with said device and said signaling means for actuating said signaling means to pro-

duce a pair of signals whose relative positions in said first time period are representative of the angular position of said low point relative to said reference point; means cooperating with said compass means and said signaling means for actuating said signaling means to produce another pair of signals whose relative positions in said second time period are representative of the angular position of said reference point relative to said predetermined compass direction; receiving means at said ground surface for receiving said signals; and recording means actuated by said receiving means for translating each of said signals into visual indicia disposed in spaced relationship relative to each other representative of the relative positions of said signals in each of said time periods.

9. In a device for measuring the inclination and direction of a well bore, the combination of: an instrument housing insertable in said bore; mechanism in said housing for measuring the angle of inclination of said housing from the vertical in terms of a plurality of angular increments; means in said housing defining a reference point thereon; device in said housing for defining a housing low point when said housing is disposed at an angle to the vertical; compass means in said housing for defining a predetermined compass direction; signal producing means in said housing; timing means in said housing for defining a time cycle including three time periods; transfer mechanism coacting with said timing mechanism for associating one of each of said time periods respectively with said mechanism, said device and said compass means; means cooperating with said mechanism and said signaling means for actuating said signaling means during the first of said time periods to produce a plurality of signals equal in number to the number of angular increments measured by said device; means cooperating with said device and said signaling means for actuating said signaling means to produce a pair of signals whose relative positions in the second of said time periods are representative of the angular position of said low point relative to said reference point; and means cooperating with said device and said compass means for actuating said signaling means to produce a pair of signals whose relative positions in the third of said time periods are representative of the angular position of said reference point relative to said predetermined compass direction.

10. In a device for measuring the direction of a well bore, the combination of: an instrument housing insertable in said bore; means in said housing defining a reference point thereon; means in said housing for defining a housing low point when said housing is disposed at an angle to the vertical; timing means in said housing for defining a time cycle including a plurality of time periods; a device in said housing coacting with said timing means and continuously movable in a closed path from a starting position corresponding to said reference point at the beginning of the first of said time periods through an indicating position corresponding to said low point to said starting position at the end of said first time period; compass means in said housing for defining a predetermined compass direction; mechanism in said housing coacting with said timing means and continuously movable in a closed path from a starting position corresponding to said reference point at the start of the second of said time periods through an indi-

cating position corresponding to said predetermined compass direction to said starting position at the end of said second time period; signal producing means in said housing; means connecting said device and said mechanism to said signaling means and responsive to movement of said device and said mechanism to their respective starting and indicating positions for actuating said signaling means to produce a plurality of signals, the position of those in said first time period being representative of the angular position of said low point relative to said reference point and the position of those in said second time period being representative of the angular position of said reference point relative to said compass direction.

11. In a device for measuring the direction of a well bore including a housing insertable in said well bore and means defining a reference point on said housing, a device for measuring the angular disposition of said reference point relative to the direction of deviation of said well bore from the vertical, comprising: an electrically conductive supporting plate in said housing disposed perpendicularly relative to the axis thereof; a commutator including a plurality of electrically conductive segments insulated from each other and disposed in positions encircling said plate and insulated therefrom for defining a circular trackway; means disposing one of said segments in a position corresponding to said reference point and electrically connecting said segment to said plate to define a monitor segment; an electrically conductive rolling member carried on said plate and movable by gravity around said trackway to the low side thereof to define a low point segment by electrically connecting said plate to the one of said segments disposed at said low side when the axis of said housing is disposed at an angle to the vertical; a rotary member engaging said commutator and movable thereover to complete an electric circuit between said rotary member and said plate through said monitor segment and through said low point segment when said rotary member is moved into contact therewith; means mounting said rotary member for movement over said commutator from said monitor segment to said low point segment to traverse the angle between said segments; and signaling means in said circuit responsive to completion thereof for producing a pair of signals spaced in time in accordance with the magnitude of the angle traversed by said rotary member.

12. In a device for measuring the direction of a well bore including a housing detachably secured to a drilling tool adapted to be moved to cause drilling of said well bore and means defining a reference point on said housing, a compass means in said housing for permitting the determination of the compass direction of said reference point, comprising: a magnetic compass needle for defining a predetermined compass direction and including a pivot seat; a pivot point carried by said housing receivable in said pivot seat for pivotally supporting said compass needle for movement to a position defining said predetermined compass direction; clamping means for moving said needle from a pivotally supported free position to a clamped position clamping said needle against movement relative to said housing and disposing said pivot and said pivot seat in spaced relation relative to each other; and means responsive to movement of said drilling tool cooperating with said clamping means for actuating said clamping means to move

said needle to said clamped position when said tool is moved to drill said bore and for actuating said clamping means to move said needle to said free position when movement of said drilling tool is stopped.

13. In a device for measuring the inclination and direction of a well bore including a housing detachably secured to a drilling tool adapted to be moved to cause drilling of said well bore and means defining a reference point on said housing, a compass means in said housing for permitting the determination of the compass direction of said reference point, comprising: a magnetic compass needle for defining a predetermined compass direction and including a pivot seat; a pivot point carried by said housing receivable in said pivot seat for pivotally supporting said compass needle for movement to a position defining said predetermined compass direction; clamping means for moving said needle from a pivotally supported free position to a clamped position clamping said needle against movement relative to said housing and disposing said pivot and said pivot seat in spaced relation relative to each other; means responsive to movement of said drilling tool cooperating with said clamping means for actuating said clamping means to move said needle to said clamped position when said tool is moved to drill said bore and for actuating said clamping means to move said needle to said free position when movement of said drilling tool is stopped; time delay means cooperating with said

pass needle for defining a predetermined compass direction and including a pivot seat; a pivot point carried by said housing receivable in said pivot seat for pivotally supporting said compass needle for movement to a position defining said predetermined compass direction; clamping means for moving said needle from a pivotally supported free position to a clamped position clamping said needle against movement relative to said housing and disposing said pivot and said pivot seat in spaced relation relative to each other; control means responsive to movement of said drilling tool cooperating with said clamping means for actuating said clamping means to move said needle to said clamped position when said tool is moved to drill said bore and for actuating said clamping means to move said needle to said free position when movement of said drilling tool is stopped; time delay means cooperating with said clamping means and said control means for actuating said clamping means to again move said needle to said clamped position a predetermined time after operation of said control means; and indicating means responsive to operation of said control means and said time delay means for indicating the angular position of said reference point relative to said predetermined compass direction when said needle is again moved to said clamped position.

15. In a device for determining the orientation of a well tool insertable in a well bore and having a reference point thereon, the combination of: a housing having a reference point thereon; means mounting said housing upon said well tool with said housing reference point in predetermined angular position relative to said tool reference point; a device in said housing for at any time measuring the angular relation between a predetermined compass direction and the location of said housing reference point; and a means in said housing for transmitting to the ground surface the measurements made by said device.

14. In a device for measuring the direction of a well bore including a housing detachably secured to a drilling tool adapted to be moved to cause drilling of said well bore and means defining a reference point on said housing, a compass means in said housing for permitting the determination of the compass direction of said reference point, comprising: a magnetic com-
